UNITED STATES PATENT OFFICE.

LA VERNE W. NOYES, OF CHICAGO, ILLINOIS.

DRIVING MECHANISM FOR WINDMILLS.

SPECIFICATION forming part of Letters Patent No. 616,134, dated December 20, 1898.

Application filed January 24, 1898. Serial No. 667,736. (No model.)

To all whom it may concern:

Be it known that I, LA VERNE W. NOYES, a citizen of the United States, residing at Chicago, in the county of Cook and State of Illinois, have invented a certain new and useful Improvement in Driving Mechanism for Windmills, of which the following is a full, clear, concise, and exact description, reference being had to the accompanying drawings, forming a part of this specification.

My invention relates to a combined grinder and driving device for windmills, my object being to provide an improved construction whereby a grinder or other mechanism may be attached to and driven by the lower end of the vertical shaft of a geared windmill and whereby in addition means may be provided for driving one or more other machines or mechanisms situated near the base of the windmill-tower.

I have illustrated my invention in the accompanying drawings, in which—

Figure 1 is a plan view illustrating the manner in which my invention may be applied to the driving of any one of a number of different machines or mechanisms. Fig. 2 is a sectional view showing the manner of connecting the grinder and the auxiliary driving mechanisms to the lower end of the windmill-shaft. Fig. 3 is a side elevation of the casing of the grinder. Fig. 4 is a view thereof from beneath. Fig. 5 is a sectional view illustrating the ball-bearings of the lower end of the vertical shaft. Fig. 6 is a view illustrating the support of the grinder and the lower journal-box of the shaft. Fig. 7 is a view of an arm for supporting the belt-guiding rollers or pulleys. Fig. 8 is a view of an adjustable arm supporting a single pulley or roller.

Like letters refer to like parts in the several figures.

The lower end of the shaft *a*, which is geared to the wind-wheel of the mill, is journaled in the barrel *b*, which carries at the lower end the casing *c* of the grinder or other mechanism, the grinder being provided with a hopper *c'*, by means of which the grain may be fed thereto, the grinder having upon the interior of the casing a grinding-ring *c²*, opposed to the face of which is provided a grinding-ring *c³*, carried upon the support *c⁴*, which is secured to the lower end of the shaft *a* and

rotates therewith. The grain passing in through the hopper *c'* works outward between the grinding-faces of the rings *c²* *c³* and passes downward into a receptacle, which may be provided therefor beneath the end of the casing *c*. In the lower end of the part *c⁴* is carried a bearing-block *d*, the lower face of which is of somewhat conical form, being gradually curved from the center toward the edges to form oblique bearing-faces, which tend to press the balls *d'* outward against the curved bearing-faces provided in the upper end of the block *d²*, which is mounted in the end of the adjustable nut *d³*, screwing in the lower end of the casing *c*. The nut *d³* is hollow, and a central hole *d¹* is provided through the block *d²*, so that any dust or dirt that may work into the ball-bearing may find an exit downward through the hole *d⁴*. The end of the support *c⁴* is hollowed, so that the edges *c⁵* thereof project downward below the ball-bearings, so that there is little tendency for the dust and chaff to pass into the bearings; but what little dust finds access to the bearing-surfaces finds a ready exit through the opening *d⁴*. The nut *d³* is provided with a notched periphery *d⁵*, into the notches of which a pivoted lever *d⁶* is adapted to rest by gravity to maintain the nut in any adjusted position.

Upon the shaft *a* above the bearing-sleeve or barrel *b* is keyed a pulley *e*, having an exterior rim *e'* and also preferably having an interior rim *e²*, both of the rims being adapted to engage driving-belts. Rotatably mounted upon the barrel *b* is an arm *f*, having a collar *f'*, which encircles the barrel *b* and which is adapted to be secured in any adjusted position by means of a set-screw *f²*. Upon the arm *f* is mounted a pair of rollers *f³* *f⁴*, and a belt *f⁵* is adapted to pass around the rim or pulley *e²* and over the rollers *f³* *f⁴*, and thence around a pulley to be driven, which may be located in any convenient position. Surrounding the barrel *b* is also provided a pair of supporting-arms *h* *k*, the arm *h* having two collars *h'* *h²* encircling the barrel, while the arm *k* is also provided with two collars *k'* *k²*, encircling the barrel and situated just above the collars of the arm *h*. The pairs of collars *h'* *h²* and *k'* *k²* are free to move relatively, whereby the arms *h* and *k* may be moved relatively into any angular position to accommo-

date the varying angles at which the belt may pass to and from the pulley. Upon the arm h is mounted a roller h^3 , and upon the arm k is mounted a roller k^3 , and a belt k^4 is adapted to be passed around the pulley e and over the rollers h^3 k^3 , the belt then passing to and around a driving-pulley situated in a convenient position. By mounting the guiding-rollers on separate and independent supporting-arms different angular positions of the entering and leaving portions of the belt may be accommodated, and the rollers may be readily adjusted for passing the belt around a large or small pulley or over a pulley arranged in a vertical or horizontal plane.

In Fig. 2 the rollers h^3 k^3 are illustrated in position to accommodate a belt adapted to pass downward after passing over the rollers. On the end of arm h is illustrated an arm l , extending upward and adapted to support a roller h^5 , whereby the belt may be carried to a pulley situated above the pulley e . A similar arm l may be provided upon each of the arms h k when desired, and separate rollers or pulleys may be journaled upon these arms, or the pulleys h^3 k^3 may be moved from one position to the other when desired. Where the driven pulleys are always below the driving-pulley, the arm l may be omitted.

In Fig. 1 I have illustrated the manner in which my invention may be employed when it is desired to provide means for driving any one of a number of machines, such as a saw, a grindstone, a feed-cutter, a corn-sheller, and the like. These various machines may be arranged in a circle around the base of the tower with the driving-pulleys preferably of the same size and arranged so that the belt k^4 may be placed upon the pulley of the particular device which it is desired to operate. The belt may thus be moved into any radial position in order to drive any one of the plurality of machines, the rollers h^3 k^3 and the arms carrying the same being moved to accommodate the belt in its new position. By this construction the driving-shaft of the windmill may be employed to operate a grinder or other mechanism mounted directly upon the lower end of the shaft, and in addition, by the employment of the auxiliary driving device any one of a number of other machines may be driven at the same time.

The lower end of the casing c is provided with walls at right angles to each other, against which the angle-bar o is adapted to be secured by means of the bolts o^1 o^2 , the lower end of the angle-bar resting upon the ground or other foundation to thus support the weight of the grinder and driving mechanism. The angle-bar o is supported and braced in position by means of the braces o^3 o^4 , which may be of wood or metal and which are secured at the upper ends to the respective faces of the angle-bar, the lower ends of the braces being secured in position in any desired manner.

Having described my invention, what I

claim as new, and desire to secure by Letters Patent, is—

1. The combination with the vertical shaft, of a barrel within which the same is journaled, a pulley on said shaft, a pair of independent supports mounted upon said barrel and independently rotatable about the same, and a guiding-roller mounted upon each of said supports, whereby the two guiding-rollers may be varied in relative position, substantially as described.

2. The combination with the vertical shaft of a windmill, of a barrel in which the lower end thereof is journaled, a pulley on said shaft, a pair of arms each mounted on collars surrounding and rotatable about said barrel and a pair of rollers for guiding the belt, one carried on each of said arms, substantially as described.

3. The combination with the vertical windmill-shaft, of a pulley having an outer rim and an inner rim lying within the outer rim, two pairs of adjustable rollers, one pair for guiding the belt passing over each of the said rims, substantially as described.

4. The combination, with the vertical windmill-shaft, of the barrel within which the same is journaled, guiding-rollers, supporting means therefor rotatably mounted upon said barrel and carrying upper and lower journals for supporting the guiding-rollers to permit the belt to pass under or over the guiding-rollers, substantially as described.

5. The combination with the vertical shaft, of a bearing-block provided at the end thereof having a conical end, an adjustable nut or part beneath the same, a bearing-block provided on the end thereof having a concave face and a central aperture communicating with the hollow interior of the nut or part, and bearing-balls interposed between said conical and concave bearing-blocks, whereby dust and dirt entering between the bearing-surfaces may escape through the central aperture, substantially as described.

6. The combination with the vertical shaft, of a barrel within which the same is journaled, a pulley on said shaft, guiding-rollers, and supporting means for said guiding-rollers rotatably mounted upon said barrel, substantially as described.

7. The combination with the vertical shaft, of a barrel within which the same is journaled, a pulley on said shaft, guiding-rollers, supporting means for the same rotatably mounted upon said barrel, and a device for locking said supporting means to the barrel to hold the supporting means in any position to which the same may be moved, substantially as described.

In witness whereof I have hereunto subscribed my name in the presence of two witnesses.

LA VERNE W. NOYES.
